CLAIM

The ornamental design for a combined cup, phone, and eyeglasses holder with key hook, as shown and described.

DESCRIPTION

FIG. 1 is a front perspective view of my combined cup, phone, and eyeglasses holder with key hook;

FIG. 2 is a rear perspective view thereof;

FIG. 3 is a top view thereof;

FIG. 4 is a front view thereof;

FIG. 5 is a right side view thereof;

FIG. 6 is a left side view thereof;

FIG. 7 is a rear view thereof;

FIG. 8 is a bottom view thereof; and,

FIG. 9 is a perspective view showing the combined cup, phone and eyeglasses holder attached to the arm of a chair. The arm of the chair in dash-dot lines in FIG. 9 is shown for environmental purposes and forms no part of the claimed design.
